UNITED STATES PATENT OFFICE.

GEORGE P. SCHREIBER, OF BALTIMORE, MARYLAND.

TOOL-SOCKET.

1,250,673.

Specification of Letters Patent. Patented Dec. 18, 1917.

Application filed December 16, 1916. Serial No. 137,452.

To all whom it may concern:

Be it known that I, GEORGE P. SCHREIBER, a citizen of the United States, residing at Baltimore, in the State of Maryland, have 5 invented certain new and useful Improvements in Tool-Sockets, of which the following is a specification, reference being had to the accompanying drawings.

This invention relates to an improved tool 10 socket whereby a plurality of tools may be interchangeably connected to the end of a suitable handle.

The present invention has for its primary 15 object to provide means whereby tools such as are used by bricklayers or other mechanics, may be easily and quickly attached to or detached from the handle of the tool.

It is another important object of the invention to provide a handle socket for tools 20 which is so constructed that it will securely and rigidly hold the shank of the tool in connection with the handle against relative movement, and with a minimum of strain upon the parts of the socket.

It is also an important object of the invention to provide a device for the above 25 purpose which is durable, serviceable and convenient in practical use, and capable of manufacture at relatively small cost.

With the above and other objects in view, 30 my invention consists in the novel features of construction, combination and arrangement of parts to be hereinafter more fully described, claimed and illustrated in the accompanying drawing, in which,

Figure 1 is a side elevation illustrating the preferred embodiment of my improved tool socket;

Fig. 2 is a longitudinal section thereof; 40 Fig. 3 is a perspective view of the body portion of the socket;

Fig. 4 is a section taken on the line 4—4 of Fig. 2;

Fig. 5 is a similar view of one of the tool 45 members;

Fig. 6 is a detail section of the tool receiving head which may be used in connection with the socket, having means to receive a plurality of relatively adjustable tool elements; and

Fig. 7 is a detail section taken on the line 7—7 of Fig. 6.

Referring in detail to the drawing, 5 designates the body portion of the tool socket which is of elongated, longitudinally tapering form, said member being cylindrical at one end, as indicated at 6, and one side being cut away for the remaining portion of the length of said member to provide the flat or plane face 7. At the inner end of this 60 flattened face 7, the end face of the cylindrical portion 6 is undercut or inclined, as at 8, and formed with a relatively narrow, transversely extending shoulder 9 extending at right angles to the face 7. The end 65 6 of the socket member is provided with an integral, longitudinally projecting flange or ferrule 10 for engagement in a recess or countersink 11 provided in the end of the tool handle H. A tapering or pointed tang 70 12 projects centrally from the end 6 of the tool member for engagement in a tapering bore formed in the end of the handle. The other end of the socket member 5 is reduced and exteriorly threaded, as indicated at 13, 75 for a purpose to be presently referred to.

The flattened face 7 of the socket member has a central, longitudinally extending channel or groove 14 formed therein, and a lug 15 projects longitudinally from the 80 shoulder 9 and the base of said channel. A second relatively small lug 16 is also formed upon the base wall of the channel in spaced relation to the lug 15.

17 designates the detachable section of the 85 tool socket which is likewise provided with a longitudinally extending channel 18 in the flat side thereof, which is adapted for engagement upon the flattened face 7 of the socket member 5. One end of this socket 90 member 17 is beveled or inclined as at 19, for engagement with the beveled face 8 of the member 5, and also has a portion of its end face disposed at right angles to the axis of said socket member, as at 20, for 95 abutting engagement against the wall or shoulder 9. The other end of the tool member 17 is also reduced and exteriorly threaded, as at 21. 22 designates an interiorly threaded, tapering sleeve or collar which is 100

adapted to be engaged upon the threaded end 13 and 21 of the socket members to tightly clamp the same together.

I have shown in the accompanying drawing a bricklayer's tool 23 having a shank 24 at one end provided with an angularly offset portion 25. In the extremity of the shank 24, a notch or recess 26 is provided, and in one face of said shank, in spaced relation to the recess, a second recess 27 is formed. In connecting the tool to the handle, it will be understood that the shank 24 is first disposed in the channel 14 of the socket member 5, the lug 15 fitting into the notch 26 while the lug 16 engages in the recess 27. The tool shank is of greater thickness than the depth of the channel 14 so that when the other section 17 of the socket is arranged in position, a portion of 20 the shank 24 will be received in the channel 18 thereof. The end of this socket member 17 is tightly engaged against the surfaces 8 and 9 of the member 5 and the clamping ring or annulus 22 then threaded upon the 25 other ends of the socket members. In this manner, it will be seen that the tool shank is tightly and securely clamped and held in the channels of the socket members, and the socket member 17 is held against trans- 30 verse shifting movement with respect to the member 9 by the shank of the tool. The inner end of the member 17 is also prevented from moving outwardly away from the member 5 by the inclined or beveled face 8 35 contacting with the beveled end face 19 of the member 17. In this manner, it will be seen that I have devised a very simple, effective and reliable handle socket whereby tools may be interchangeably connected 40 therewith. A single handle may thus serve for use in connection with a large number of tool elements employed for different purposes.

In Fig. 5 of the drawing, I have shown 45 a rectangular tool head 28 which is obliquely inclined with respect to its shank 29, said shank being provided with means for connection to the handle socket as above described. The hub 28 has a longitudinal 50 opening 30 extending therethrough, in which a plurality of tool blades 31 are adapted to be arranged. 32 designates a clamping or set screw threaded in one side of the head 28, whereby the series of tool blades 55 may be tightly clamped and held against movement. By loosening this screw any one of the tool elements may be projected beyond the others, as indicated in Fig. 5, in position for active use. These tool blades 60 are preferably of different widths to be used under different circumstances. This type of tool head is especially desirable for use by bricklayers in removing mortar from the face of a wall, particularly beneath the

cornices or ledges, as it enables the workmen to freely manipulate the tool without striking the hands or knuckles against projecting portions of the wall. This is also true of the other tool illustrated in Fig. 4, since it will be obvious that by providing 65 the offset shank thereon, the handle and consequently the hand of the workman will be disposed at some distance from the wall face in the use of the tool.

From the foregoing description, taken in 70 connection with the accompanying drawing, the construction, manner of use and several advantages of the device will be clearly and fully understood. By the provision of my improved socket, the tool elements may be 75 easily and quickly connected to the handle or detached therefrom, thus reducing the expense incident to the use of a large number of tools, as a single handle may be provided with the entire tool set. It is, of course, apparent that the socket may be 80 made in various sizes and of other shapes than that shown in the drawing. The form, construction and relative arrangement of the several detail parts of the device are also 85 susceptible of considerable modification and I, therefore, reserve the privilege of adopting all such legitimate changes as may be 90 fairly embodied within the spirit and scope 95 of the invention as claimed.

Having thus fully described my invention, what I desire to claim and secure by Letters Patent is:

1. A tool socket including a body member having a cylindrical end portion and a 100 longitudinally extending, flattened face provided with a longitudinal channel therein, said member being provided with a lug at the inner end of the channel projecting outwardly therefrom beyond the flattened face 105 of said member and adapted for engagement by the shank of a tool member, a complementary socket member adapted for engagement upon the flattened face of the body member and also provided with a channel 110 to receive the shank of the tool member, said lug engaging in one end of said channel, the cylindrical end portion of the body member being provided with a transversely beveled face at the inner end of the channel 115 in said member and said second named socket member also having a beveled end face to engage the beveled face of the body member whereby said members are held against relative lateral movement, and 120 means detachably engaged upon the other ends of the socket members to clamp the same together.

2. A tool socket including complementary 125 socket members each having a longitudinally extending channel, said channels when arranged in mating relation receiving the shank of the tool, one of said members being

provided with spaced lugs projecting from the base wall of the channel therein, the shank of the tool being recessed to receive said spaced lugs, said socket members being further provided with co-acting means to prevent their relative movement in a direction at right angles to the axis of the socket, the corresponding ends of said socket members being threaded, and a

clamping sleeve adapted to be engaged upon the threaded ends of said members to clamp the same upon the tool shank.

In testimony whereof I hereunto affix my signature in the presence of two witnesses.

GEO. P. SCHREIBER.
